UNITED STATES PATENT OFFICE

117,371

DESIGN FOR A PARKING METER

Jay Mansfield Johnson, Grosse Pointe Park,
Mich.

Application January 3, 1939, Serial No. 82,124

Term of patent 3½ years

To all whom it may concern:

Be it known that I, Jay Mansfield Johnson, a citizen of the United States, residing at Grosse Pointe Park, in the county of Wayne and State of Michigan, have invented a new, original, and ornamental Design for a Parking Meter, of which the following is a specification, reference being had to the accompanying drawing, forming part thereof, wherein:

Fig. 1 is a side elevational view;

Fig. 2 is an elevational view showing the opposite side; and

Fig. 3 is a top plan view of a parking meter, showing my new design.

I claim:

The ornamental design for a parking meter, as shown.

JAY MANSFIELD JOHNSON.
